UNITED STATES PATENT OFFICE.

LUCIAN B. ROBB, OF CINCINNATI, OHIO.

DRY CLOSET.

SPECIFICATION forming part of Letters Patent No. 365,202, dated June 21, 1887.

Application filed January 10, 1887. Serial No. 223,869. (No model.)

To all whom it may concern:

Be it known that I, LUCIAN B. ROBB, a citizen of the United States, residing at Cincinnati, in the county of Hamilton, State of Ohio, have invented certain new and useful Improvements in Dry Closets, of which the following is a specification, reference being had therein to the accompanying drawings.

My invention comprises a novel structure wherewith human excrements can be economically and effectually disposed of without the annoyances incidental to the use either of water or earth closets, the preferred arrangement of said structure being, briefly, as follows: An oven or drying-receptacle is built in the lower part of a house, and usually in the cellar, said oven being of such a capacity as to contain the excrements that may accumulate for several months, or a longer period of time, if desired, the excrements being discharged into this receptacle through vertical soil-pipes that lead directly up into rooms or closets. The upper ends of these soil-pipes are provided with seats, to which ordinary lids are hinged, said lids being free from valve-operating devices or other complicated and expensive appliances, in order that the simple opening of these hinged covers will afford a free and unobstructed dropping of the excrements down said pipes and directly into the receptacle at the base of the structure or apparatus. Furthermore, the oven has a special shaft, the upper end of which projects above the building, so as to secure the most complete ventilation, this withdrawal of the foul air being rendered more thorough by connecting one or more stove-pipes to said shaft, the kitchen stove-pipe being preferred, because of its almost constant use. Small lateral flues connect the soil-pipes with the ventilating-shaft, which flues may be provided with dampers or regulators, and when the oven is sufficiently filled with excrements these dampers are opened, and a fire is then built in said oven and is kept up until its contents are sufficiently dried or consumed, so as to be readily removed without creating a nuisance, as hereinafter more fully described.

In the annexed drawings, Figure 1 is a vertical section through a house provided with my preferred arrangement of dry closets. Figs. 2 and 3 are vertical sections of modifications of my invention. Fig. 4 is an enlarged

section through the flue that leads from the upper soil-pipe into the ventilating-shaft of 55 the oven.

A represents the cellar, basement, or other lower portion of a house, and B C D are upper rooms or closets of the same, said cellar having an oven, E, in it, which oven is usually 60 built of masonry. The exact capacity of this oven is immaterial; but it is preferred to make it sufficiently large to contain all the excrements that may accumulate for a number of months, or for a year or more, if desired. 65

F is a grating or perforated plate upon which the excrements are deposited, and beneath this grating a bed of sand, G, is placed to absorb the urine.

e e are the fire-doors of the oven, and H I J are soil-pipes leading from the latter up into the respective rooms or closets B C D, the upper ends of said pipes having seats h i j, covered with hinged lids h' i' j'. These soil-pipes are preferably of brick, and have near their seats small flues K, which allow all odors from said pipes to escape into the ventilating-shaft L. This shaft, like the soil-pipes, projects vertically from the top of the oven, and the outlet of said shaft is a sufficient distance above 75 or away from the house to render the latter free from any offensive or injurious gases. This shaft may constitute the only ventilating 80 appliance of the oven, the natural draft being depended on for drawing off the odors; but I prefer using a forced draft, especially as it can be maintained without adding to the regular 85 running expense of the closet. The preferred method of producing this artificial or forced draft is by connecting the pipe m of a kitchen 90 stove or range, M, with the shaft L.

From the above description it is apparent that whenever a person uses a closet in either of the rooms B, C, or D the deposits drop directly down the respective soil-pipes into the 95 oven E, the excreta and paper lodging upon the grating F, while the urine runs through the latter and is taken up by the bed of sand, G, or other cheap absorbent. It is also apparent that the shaft L is constantly and automatically drawing off the foul odors and gases from the oven, and also from any fecal matter that may adhere to the soil-pipes, the latter being ventilated through the flues K. As a result of this thorough ventilation of the oven 100 and its accessories the house is at all times 105

odorless, and the expense and annoyances incidental to the use of water or earth closets are dispensed with. When the oven is about full, the doors *e e* are opened, and a fire is then kindled beneath the grating *F*, for the purpose of completely consuming the excrements and all paper or other litter dropped therewith. The fire is kept up until these substances have been dried or converted into a powdery mass that is perfectly odorless and can be handled without defiling a person; and when this result has been obtained the fire is put out and the contents of the oven removed without occasioning any nuisance to the occupants of the house. While the fire is in progress the various passages, *H, I, J, K, and L*, serve as flues or chimneys for the oven, and, as a natural result, these passages are cleaned of any deposits that may have accumulated in them.

The above is a description of my dry closet when it is built complete in a house especially adapted for it; but as the closet must frequently be erected in old buildings some provision is necessary for ventilating the oven from an ordinary flue or chimney. This communication of the oven with a flue may be accomplished in various ways, one method being shown in Fig. 2, where the receptacle *E* is built up close against the flue *L'* and has a ventilating-passage, *K*, leading into the latter. Oven *E* has a single soil-pipe, *N*, surmounted by a seat, *n*, and hinged lid *n'*. Furthermore, said oven has a series of fire-doors, *e*, at different elevations, but no grating, the excrements being deposited directly upon the sand bed *G*. When this oven is full, either or all the doors *e* are opened and the contents of the receptacle are saturated with coal-oil or other comparatively cheap burning-fluid, after which act the oil is ignited and the excreta consumed or dried, as previously described.

m is a stove-pipe that communicates with the flue *L'*; but in some houses it is impossible to arrange the oven in close contact with an ordinary flue, and in this event the expedient seen in Fig. 3 may be adopted. Here the oven *E* is somewhat remote from the ventilating-flue *L'*, but has a pipe, *K'*, communicating therewith, through which pipe the foul gases and vapors are being constantly drawn off. This oven has a single soil-pipe, *O*, seat *o*, and hinged lid or cover *o'*.

Fig. 4 shows one of the lateral flues *K* provided with a damper or regulator, *P*, the diameter of which is slightly less than the diameter of the flue, in order that the latter may never be entirely closed. This damper is normally closed, as indicated by the dotted lines; but when the contents of the oven are to be burned, said damper is turned down to a horizontal position, to allow the fire and smoke to traverse said flue.

R in Fig. 1 shows a slide or damper at the lower end of shaft *L*, which slide may be closed at all times, except when fire is to be started in the oven, and then it is opened. The dotted line *L''* in said illustration shows

that the ventilating-shaft may extend only from the longest soil-pipe, *J*, thus dispensing with that portion of the shaft between the oven and the upper floor of the house. The ventilation of this shaft *L''* may be effected by means of a stove, *M'*, and pipe *m'* in the upper room of the house.

I am aware it is not new to provide various forms of ovens and similar receptacles for burning human excrements before removing them from a closet or other structure. Therefore I do not claim this feature, broadly, but limit my invention to the combination of excreta-receptacle, ventilating-shaft, and one or more soil-pipes and lateral flues, as herein described.

I claim as my invention—

1. The combination, in a dry closet, of a fire-proof excreta-receptacle situated at the base of the structure, a series of independent soil-pipes, and a ventilating-shaft communicating therewith, the upper end of one soil-pipe being connected with the adjacent soil-pipe by a lateral flue, and the highest soil-pipe having a lateral flue that discharges into said ventilating-shaft, and means being provided for drying or burning the contents of said receptacle and causing the products of combustion to traverse said pipes, flues, and shaft, which shaft has the pipe of a cooking or heating apparatus leading into it, in order that a forced draft may be induced in the closet without employing a special appliance for the purpose, as herein described.

2. The combination, in a dry closet, of a fire-proof excreta-receptacle situated at the base of the structure, a soil-pipe and ventilating-shaft communicating therewith, and a dampered lateral flue that connects the upper end of said pipe with said shaft, which damper can be opened to permit the products of combustion to traverse said pipe, flue, and shaft when said receptacle is fired, as herein described.

3. The combination, in a dry closet, of a fire-proof excreta-receptacle, *E e*, soil-pipes *H I J*, lateral flues *K*, ventilating-shaft *L*, and a smoke-pipe, *m*, communicating with a cooking or heating apparatus, *M*, and serving to create a forced draft within said ventilating-shaft, said receptacle being provided with means for burning or drying its contents, as herein described.

4. The combination, in a dry closet, of a fire-proof excreta-receptacle situated at the base of the structure, a soil-pipe and ventilating-shaft communicating therewith, a lateral flue connecting the upper end of said pipe with said shaft, means for drying or burning the contents of said receptacle, and an absorbent bed at the bottom of said receptacle, as herein described.

In testimony whereof I affix my signature in presence of two witnesses.

Witnesses: LUCIAN B. ROBE.
